(57) **CLAIM**

The ornamental design for an imaging apparatus as shown
and described.

DESCRIPTION

FIG. 1 is a top front left perspective view of an imaging
apparatus according to the claimed design.

FIG. 2 is a left side view of the imaging apparatus.

FIG. 3 is a right side view of the imaging apparatus.

FIG. 4 is a rear view of the imaging apparatus.

FIG. 5 is a front view of the imaging apparatus.

FIG. 6 is a top view of the imaging apparatus; and,

FIG. 7 is a bottom view of the imaging apparatus.

The dash-dash broken lines in the drawings illustrate portions
of the imaging apparatus that form no part of the
claimed design.

The dash-dot broken lines in FIG. 7 define the boundary of
the claim, which extends to the boundary but does not
include the boundary.
